CHEMICAL PROCESS

Charles E. Hemminger, Westfield, N. J., assignor
to Standard Oil Development Company, a cor-
poration of Delaware

Application April 9, 1941, Serial No. 387,583

2 Claims. (Cl. 196—55)

The present invention relates to the art of treating hydrocarbons and, more particularly, it relates to the art of obtaining from relatively heavy or high-boiling hydrocarbon oils increased quantities of fractions boiling substantially within the gas oil range.

As is generally known, ordinarily, the first refinery operation in treating a crude petroleum oil to obtain commercially valuable constituents thereof is to subject it to simple distillation or "topping" to remove from the crude oil those constituents boiling up to and including the so-called gas oil range, that is to say, those constituents are removed, by distillation, which boil up to about 700°—850° F. The residue, of course, contains constituents which may be processed to recover valuable constituents such as lubricating oil, paraffin wax, petroleum asphalt, and the like, depending upon the nature and origin of the original crude. There are, however, occasions when a reduced crude or topped crude, due to commercial demand or for some other reason, is processed to recover additional quantities of gas oil, heating oil, fuel oils, and the like.

In current practice there are at least two general methods for processing reduced or topped crudes to recover additional quantities of gas oil and fractions of similar boiling range. The first of these is the so-called viscosity-breaking operation in which the crude oil is subjected to an elevated temperature for a relatively short period of time to recover an additional quantity of gas oil. In general, viscosity breaking is a relatively mild thermal treatment producing from 5% to 15% gasoline, as well as gas oil, and the gas oil obtained from such an operation is usually a suitable feed stock for a catalytic cracking operation since it contains relatively small amounts of aromatic hydrocarbons having more than two benzene rings in a condensed nucleus. The viscosity reducing operation also produces a petroleum tar and heavy oil which may be further heat treated to produce asphalts and road paving compositions or sold as a liquid fuel oil. The thermal treatment of the heavy constituents of the residuum partially cracks it and reduces its viscosity. As a result less gas oil is necessary to blend therewith for a fuel oil of saleable viscosity.

The second method, the coking of reduced crudes, is a much more drastic heat treatment of the reduced crude than is the vis-breaking operation since it results usually in the production of volatilizable hydrocarbons such as gas oil, gasoline, and light hydrocarbons, together with a solid coke. The gas oil from the coking opera-

tion ordinarily is not considered as good a feed stock as that produced by viscosity reducing, for a catalytic cracking operation, since the former is quite apt to contain appreciable quantities of naphthalene, anthracene, phenanthrene, benzanthrene, and other cyclic hydrocarbons containing a plurality of benzene rings in a single nucleus. These multi-ring aromatic compounds tend to produce excessive amounts of coke on the catalyst in a catalytic cracking operation. Moreover, 15% to 35% of gasoline is produced and it has a low octane number. It is desirable to produce a minimum of gasoline in either of these two thermal operations to have the highest final octane number on the crude when using catalytic cracking of gas oils.

I have discovered a means of treating a reduced petroleum crude operation which, in its broader aspect, involves first subjecting the reduced crude to a viscosity-breaking operation in the presence of a powdered carbonaceous material and thereafter subjecting the tar bottoms from the viscosity breaking operation to a coking operation.

I have found that I obtain increased quantities of gas oil from the viscosity breaking operation, which gas oil has excellent qualities as a feed stock for a catalytic cracking operation. In the coking operation, I, of course, produce a gas oil which is not, as such, particularly suitable for catalytic cracking but may however be employed as a feed stock in a thermal cracking operation. According to my present process I may subject the gas oil from the coking operation to a treatment with solvents such as SO_2 wherein I am enabled to improve the quality of the gas oil by dissolving out the polycyclic aromatics and mixing the raffinate from the solvent treatment with the gas oil from the viscosity reducing operation to form a suitable charging stock for a catalytic cracking operation.

The object of my invention, therefore, is to transform increased quantities of a heavy petroleum oil into gas oil of a quality suitable for use as a catalytic cracking stock.

Another object of my invention is to reduce the viscosity thereof, to produce a gas oil, a relatively heavy hydrocarbon oil in the presence of a granulated or subdivided carbonaceous material such as petroleum coke and thereafter to coke the tar and heavy oil from the viscosity reducing operation to produce a further quantity of gas oil, the added coke being present also in the coking operation.

A further object of my invention is to subject a

heavy petroleum oil residuum to viscosity reducing in the presence of added granular petroleum coke, to coke the residual tar and heavy oil, to solvent treat the gas oil from the coking operation and to combine the raffinate from the latter operation with gas oil from the viscosity reducing operation.

Other objects and advantages of my invention will more fully appear hereinafter.

The present invention is fully disclosed in the following specification and claims, reference being had to the accompanying drawing.

Fig. 1 shows a diagrammatic flow plan serving to indicate a preferred modification of my present improvements.

Referring in detail to the drawing, an East Texas crude oil of about 38° A. P. I. gravity is introduced into the system through line 1 and thence discharged into a coil 3 disposed in a suitable furnace setting 5. The oil is heated in coil 3 to a temperature within the range of from about 500-900° F., under a gauge pressure of 5 to 500 lbs./square inch, whereupon the heated oil is withdrawn from coil 3 through line 6 and thence discharged into fractionating tower 8 from which overhead products containing gasoline and gas are withdrawn through line 10 and heavy naphtha and gas oil through side streams 9 and 11 as separate products for sale as such or further processing.

The heavy oil bottoms separated in drum 8 which may, for example, have an initial boiling point of 700° F. and a gravity of 18° A. P. I. are withdrawn through line 12 and discharged through injector 19 and pump 21 into a second heating coil 14 disposed in a furnace 15. Just prior to discharge of the oil in line 12 into coil 14, petroleum coke having a particle size of from say 100 to 400 mesh is withdrawn from a feed hopper 16 through a star feeder 17 and a conduit 18 and thence fed into mixing means 19 to form a slurry of coke and oil. The amount of coke thus added may vary in rather wide limits, say 1 to 100 parts by weight of coke per 100 parts of oil, with 5 to 50 parts preferred. The oil is heated in coil 14 to a temperature of from about 800° F. to 1000° F. while maintaining a coil outlet pressure of from 1 to 1000 lbs./square inch gauge. The oil feed rate to the coil may vary from 1 to 30 vol. of oil per vol. of coil per hour. The oil is withdrawn from coil 14 through line 20 and discharged into a second separation drum 25. The vapors containing gas oil and light products are withdrawn from separation drum 25 through line 28 and may be delivered to a fractionating tower 29 from which normally gaseous hydrocarbons and gasoline are withdrawn through line 32 while a gas oil fraction is recovered through line 34. The virgin gas oil recovered from fractionating tower 8 through line 11 may be combined with that in line 35 and the combined gas oils may be delivered to storage (not shown) as a suitable source of supply for a catalytic cracking feed stock. The presence of the fine powder in the vis-breaking operations allows higher operating temperatures and shorter contact times than heretofore employed in vis-breaking since carbon formation in the tubes is prevented by the scrubbing action of the coke particles and their absorptive properties for asphaltic material in the tar.

The heavy oil containing the added coke is withdrawn from drum 25 through line 30 by means of pump 31 and discharged into a third coil 36 disposed in a furnace setting 37 where the oil is heated to temperatures within the range

of from about 900° F. to 1100° F. This coil is merely a preheating coil and the temperatures indicated are attained as rapidly as possible, say from 1/2 to 10 minutes being sufficient time of residence of the oil in the coil to acquire said temperatures. The oil is withdrawn from coil 36 through line 40 and discharged into a coking drum 43. To attain continuity, it will be readily understood by those skilled in this particular art, that two or more coking drums should be employed so that while one or more are being decoked, the other or others may be employed in the on-stream operation. The oil is subjected to the temperatures indicated, namely, 800° F. to 1100° F., and preferably to a superatmospheric pressure which may be as high as 750-1000 lbs./square inch. Drum 43 may be a simple upflow drum for coking or it may be any other form of coking apparatus such as a heated coil, continuous coker producing a powdered coke, refractory hearth coker or other types known to the art. The vapors are withdrawn from the coking drum through line 46 and delivered into a fractionating column 48. Several fractions may be recovered from fractionating column 48, such as gasoline and higher hydrocarbons through line 50, domestic heating oil through line 52, and a heavier oil through line 55. The bottoms from the tower may, if desired, be recycled through line 58 to line 30 for further treatment, or may be withdrawn through line 60 and processed to recover desired products such as heating fuels.

Preferably, the gas oil recovered through line 55 from tower 48 is treated with a solvent such as liquid SO₂, in a suitable tower 62, the SO₂ being supplied through line 80. A raffinate substantially free of aromatics containing two or more benzene rings in a condensed nucleus is recovered from treating tower 62 through conduit 64 to still 66, subsequently discharged through line 68 to tower 70 to be washed with an alkaline substance such as aqueous sodium carbonate or caustic soda, and thence pumped by pump 72 through transfer line 71 to line 35 where it admixed with the gas oils previously produced as hereinbefore explained.

The washing solution may be discharged into tower 70 through line 78 and removed through line 79.

The SO₂ associated with the raffinate is recovered from still 66 through line 76, compressed and refrigerated in 78 and recycled through line 80 to treating vessel 62.

Meanwhile, the extract formed in tower 62 may be withdrawn therefrom through line 85. This extract may be freed of SO₂ and the hydrocarbons may be treated to produce more or less high-powered solvents since they contain aromatics, or the hydrocarbons may be employed for some other suitable purpose.

The solvent treatment herein described is an incident of my complete process, and as such, does not involve invention by me, since I may employ any conventional solvent treating technique and any known solvent.

Referring again to separator 25, if some of the finer particles of coke are carried overhead through line 28, the vapors are preferably delivered to one or more cyclone separators to remove suspended or entrained coke. Also a portion of the coke formed in the process may be ground and reintroduced into the system through hopper 16. It will be understood, of course, that coke from some extraneous source may be added

to the oil in line 12, that is coke from some process other than the one just now described, or even coke derived from destructive distillation of coal may be employed. It may also be desirable to add the coke to mixer 19 at an elevated temperature so that a portion of the heat required could be obtained by heat transfer from the coke. Furthermore, superheated steam may be employed to assist in the heating of the oil in coils 3, 14 and 36 and the vaporizations in drums 25 and 43.

While it is normally desirable to fractionate the products from coke drum 43 separately to give desirable products, the vapors from drum 43 may be introduced by line 47 into line 20 and tower 48 is not used. Under these conditions the vapor products from both the viscosity breaking and the coking operations issue from 25 through line 28. The temperature and pressure in tower 25 may be varied so that controlled amounts of gas oil introduced in the vapors in line 20 are withdrawn through line 28 or withdrawn through line 30 for coking. The vapors in line 28 may be taken directly to a catalytic cracking unit or may be fractionated in tower 29 to give gas, gasoline and/or light gas oil overhead in line 32 and gas oil in line 34 for feed to catalytic cracking unit.

Moreover, the described combination of viscosity reducing and coking has advantages over one step coking of the residuum even where the untreated gas oils from the two operations are combined (i. e. where the gas oil from the coker 43 is not treated with a solvent). In the single step coking operation about 30 gallons of low octane number gasoline are produced from 100 gallons of original residuum. In the two step operation only 10 gallons of gasoline are produced, leaving about 40 gallons of pitch to be coked. The gasoline in the latter operation is 12 gallons, making a total of 22 gallons of low octane gasoline in the coking of the residuum. As is well known in the art, the less gasoline produced in the formation of a gas oil in coking or viscosity reducing, the less is the resulting coke yield and the greater is the quantity and quality of the gas oil produced. The following is an illustrative example of the one versus the two stage operation.

Feed—18% East Texas residuum

Coking	One stage	Viscosity reducing plus coking
Gasoline.....	volume per cent.....	20
400-750° gas oil.....	do.....	60
Coke.....	weight per cent.....	16

Although the combination operation (without solvent treatment) has been discussed as a source of gas oil for catalytic cracking, the gas oil, separate or mixed, may also be used for thermal cracking. In the latter case, the higher aniline point, 195° F. as against 166° F. of the combination operation indicates a more paraffinic stock which gives a higher yield in thermal cracking.

Of course, the gas oils are a superior product for other uses as heating oils and Diesel fuels. The decreased coke and low octane number gasoline yields are corollary advantages. Moreover, the volume of the expensive coke drum and attendant equipment is decreased by the absence of the vapors produced in the viscosity reducing operation.

To review briefly, the present invention relates primarily to a process of preparing a feed stock for a catalytic cracking operation and is characterized by the features of viscosity reducing, followed by coking, of a heavy petroleum oil in the presence of powdered coke, or the like, the powdered coke being rather finely ground and having as a particle size below 20 mesh. The presence of the coke in the viscosity reducing operation improves the yield and quality of the gas oil from the standpoint of a catalytic or thermal cracking feed stock, and substantially all of the coke which is added to the process is finally withdrawn from the viscosity reducing zone with the tar. Hence, it is desirable to coke the heavy oil and tar rather than to attempt to process it to form asphalt or road paving compositions, since tar and asphalt should be free from hardened particles of coke.

Many modifications of my invention falling within the spirit and scope thereof will suggest themselves to those who are familiar with this art.

What I claim is:

1. In a process for producing gas oil suitable for cracking operations from heavy petroleum residual crudes, the steps which comprise viscosity breaking the reduced crude by passing it through a long, narrow, heated conduit along with finely powdered coke, whereby the maximum of gas oil is produced along with the minimum quantity of gasoline and a heavy cracked residuum, separating the said products, coking the cracked residue whereby gasoline, gas oil and coke are produced, extracting the gas oil with a solvent capable of removing aromatic hydrocarbons and combining the non-aromatic fraction of the extracted gas oil with the gas oil obtained in the viscosity breaking operation to form a feed stock for a new cracking operation.

2. The method of producing a gas oil suitable as a charging oil to a catalytic cracking operation which comprises subjecting a heavy and residual petroleum oil to a viscosity reducing operation in the presence of divided coke, recovering a quantity of gas oil from the viscosity reducing operation, subjecting heavier oil and tar residue, remaining after removal of said gas oil from the products of the viscosity reducing operation, to a coking operation to produce a further quantity of gas oil, treating the said gas oil with a selective solvent to remove aromatic hydrocarbons from said gas oil, and combining the gas oil produced in the coking operation, after removal of the aromatics, with the gas oil produced during the viscosity breaking operation.

CHARLES E. HEMMINGER.
